UNITED STATES PATENT OFFICE.

CHARLES G. CURTIS, OF NEW YORK, N. Y.

ELASTIC-FLUID TURBINE.

1,071,887.

Specification of Letters Patent. Patented Sept. 2, 1913.

Application filed December 14, 1911. Serial No. 665,604.

To all whom it may concern:

Be it known that I, CHARLES G. CURTIS, a citizen of the United States, residing in the borough of Manhattan, city, county, and State of New York, have invented a new and useful Elastic-Fluid Turbine, of which the following is a specification.

The object I have in view is the improvement of the economy of elastic fluid turbines 10 when running under low power.

The invention is primarily intended for the use of steam as the specific kind of elastic fluid employed, but the invention is not so limited, to the use of steam.

15 The invention is particularly applicable for marine turbines, particularly for use in war vessels, which have a certain maximum speed but which are intended to be run for considerable periods of time at slower speeds 20 or under low power. The comparatively poor economy of marine steam turbines under low powers in commercial vessels, or in cruising conditions in naval or other vessels, is due to the fact that the reduced power is 25 generally obtained by throttling or otherwise greatly reducing the steam flow through the turbine. This reduction of the steam flow results in reducing very greatly the pressure in the first stage and means an 30 extremely large pressure-drop from the boiler pressure to that of the first stage of the turbine. Where the first stage is built in the form of an impulse type of turbine, this means an exceedingly high velocity de- 35 livered to the wheel by the nozzle, and since the velocity of the buckets is very low because of the reduced speed of revolution, the efficiency of the first stage, which does a very considerable part of the work under 40 low powers, is greatly reduced. In some cases, the efficiency becomes as low as fifteen per cent.

The object of my invention, therefore, is to overcome this difficulty and to provide 45 means for very greatly increasing the efficiency of the early portion of the expansion range utilized in the turbine at low powers. The difficulty with the first stage of a turbine operating at greatly reduced powers is 50 that the pressure-drop is much too great to be efficient, (in the case of some warships from 250 lbs. down to 15 lbs. absolute in one step) while the volume is much too small.

According to my invention, I aim to re- 55 duce the pressure-drop in the first or early

stages of the turbine to a point where it can be efficiently utilized by the slow moving buckets, and I accomplish this by converting the energy of high pressure and small volume steam into energy of steam of much 60 lower pressure, but much larger volume, the energy of expansion being transferred from the high pressure to the low pressure steam. This low pressure steam is then converted into work in the first stage or the early part 65 of the turbine in a much more efficient manner, and the net result is a substantial gain in the output of the entire machine.

These and further objects will more fully appear from the following specification and 70 accompanying drawings, considered together or separately.

Figure 1 is a schematic view, partly in section, showing a portion of a multi-stage turbine and a device in connection therewith, embodying my invention. Fig. 2 is a view similar to Fig. 1, but not in section, and showing a modification. Fig. 3 is an enlarged view in section on the line 3--3 of Fig. 4, of the device shown in Fig. 2. Fig. 4 80 is a sectional view on the line 4--4 of Fig. 3.

In all of the views, like parts are designated by the same reference characters.

There are various ways in which the energy of high pressure and low volume steam 85 can be converted into energy of steam of low pressure and large volume. In Fig. 1, I illustrate a rotary turbine compressor, the high pressure steam passing through a turbine in which it develops power and this 90 power being transferred to a compressor or reverse turbine which takes steam out of one part of the turbine, compresses it up to a certain point, and delivers it to a previous stage in the turbine, this steam passing continually through the turbine and through the compressor alternately, in a continuous circuit. Another way of compressing the steam, illustrated in Figs. 2, 3 and 4, is by means of a device with an aspirator or injector action, the high pressure steam flowing at high velocity after expansion in suitable nozzles and bringing in contact with it thin streams of the low pressure steam which are drawn along by frictional action, 105 the velocity of the resultant mixture being converted into pressure by flowing through proper shaped passages.

Referring to Fig. 1, which illustrates a turbine with a number of stages, which are 110

purely for illustration, 1 is the turbine, having the first stage 2, in the form of an impulse turbine. The high pressure steam is admitted through the nozzles 3, 3, when the turbine is run at full powers. The second stage 4, is in the form of a drum turbine having complete peripheral admission; the third stage 5, is a turbine of the same type having the steam flowing in the reverse direction by means of passages 6. At full powers or high speeds, the steam passes in succession through the stages 2, 4 and 5. At low powers, or for cruising speeds, the stage 2 is cut out, no steam being admitted to the nozzles 3, 3, unless a small amount be utilized to prevent the blades in that stage from absorbing power. At these low powers, or cruising speeds, the steam is admitted in the first instance through the passage 7, to a high pressure turbine 8. This turbine is so proportioned that it will work in an efficient manner with the small volume of steam admitted under low powers. The exhaust in this turbine will go through the passage 9, into the space 10 between the first and second stages, and will pass through the succeeding stages, doing work therein. Coupled to the shaft of the turbine 8, is a compressor 11, which may be in the form of a stage compression rotary compressor, or a reverse steam turbine such as illustrated in my co-pending application for Patent, No. 601606, filed August 4, 1896, or No. 360058, filed March 1, 1907. This compressor takes steam from the discharge of the second stage 4, through the passage 12, and after compressing it, delivers it to a passage 13, into the space 10, so that it will pass through the stage 4, doing work therein. The large volume of low pressure steam discharged from the second stage has its pressure raised by means of the compressor to a point where the pressure-drop between the inlet and outlet of that stage can be efficiently utilized under conditions of bucket speed existing.

Assuming, for example, under ordinary cruising conditions, at say one-tenth of the maximum power of the turbine, the first stage 2 does one-third of the work, the two other stages together do the other two-thirds of the work; and assuming that the efficiency of the first stage which at one-tenth power is only 15%, by means of the apparatus above described, if the stage 4 is given an efficiency of say 37½%, then the output of this stage will be increased two and one-half times, and the output of the entire apparatus will be increased 50%. It will be understood, therefore, that if the efficiency of the first stage in operation or the early part of the turbine, can be improved to this extent by operating it with steam at quite a low pressure, giving a velocity which the buckets are adapted to utilize efficiently, but of larger

volume or greater quantity, it is apparent that the output of the apparatus can be very materially increased without any increase in the initial steam flow. The cruising radius of the vessel can in this way be increased by the mere addition of a device for converting pressure into volume. This device I denominate a "pressure transformer."

According to the apparatus illustrated in Figs. 2, 3 and 4, in place of the turbine 8, and rotary compressor 11, I employ a device 14, working as an injector or aspirator. connection 17, and passes then through the pipe 15, and is ejected through the annular expanding nozzles 16. The low pressure steam from the second stage 4 passing through the pipe 12 of Fig. 1, enters the connection 17, and passes then through the annular passage 18, this passage being in line with the nozzles 16. The high pressure steam in the passage 15 will be converted into velocity through the nozzles 16, and this steam at high velocity will draw in or inject the steam of low pressure and great bulk as passed through the stage 4. This steam will be compressed and exhausted through the pipe 20 into the space 10 in advance of the second stage. After passing the point where the two streams of steam come together, the passage gradually enlarges in cross-section, thus causing the velocity of the mixture to be converted into pressure.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent is:—

1. An elastic fluid turbine having a stage of high pressure, means for admitting fluid of high pressure to such stage, a stage of lower pressure receiving the fluid discharged from such high pressure stage, means converting energy of fluid, at low pressure and large volume, discharging from such stage of lower pressure, such means being operated by fluid of high pressure and small volume, and means for admitting such high pressure fluid to such converting means, independently of the high pressure stage.

2. An elastic fluid turbine having a stage of high pressure, means for admitting fluid of high pressure to such stage, a stage of lower pressure receiving the fluid discharged from such high pressure stage, means operated by fluid at high pressure and small volume, operating upon the dis-

- charge of said stage of lower pressure, to compress said fluid said means being operated by fluid independently of the first stage.
3. An elastic fluid turbine having a stage 5 of high pressure, means for admitting fluid of high pressure to such stage, a stage of lower pressure receiving the fluid discharged from such high pressure stage, a fluid compressing device separate from the 10 stage of lower pressure, said device being operated by fluid of high pressure and small volume, to compress fluid discharged by said stage.
4. An elastic fluid turbine having a stage 15 of high pressure, means for admitting fluid of high pressure to such stage, a stage of lower pressure receiving the fluid discharged from such high pressure stage, a fluid compressing device coördinated with said stage 20 of lower pressure in such a manner that fluid flows in circuit through said stage and compressor and is compressed by the latter, and expands in the former, said compressor being operated by fluid of high pressure and 25 small volume.
5. An elastic fluid turbine having a stage 30 of high pressure, means for admitting fluid of high pressure to such stage, a stage of lower pressure receiving the fluid discharged from such high pressure stage, and a fluid compressing device coördinated with the 35 stage of lower pressure in such a manner that fluid of low pressure and large volume will flow in circuit through the two, means for operatively connecting fluid of high pressure and small volume with said device, whereby said device will be operated by the expansion of the high pressure fluid, means for discharging said fluid after expansion into the stage, and means for exhausting a portion of the discharge from 40 said stage into a second stage of lower pressure.
6. An elastic fluid turbine, having a stage of high pressure, means for admitting fluid of high pressure to such stage, a stage of lower pressure receiving the fluid discharged from such high pressure stage, and a fluid compressing device coördinated with the stage of lower pressure in such a manner that fluid of low pressure and large volume will flow in circuit through the two, means for operatively connecting fluid of high pressure and small volume with said device, whereby said device will be operated by the expansion of the high pressure fluid, and means for exhausting a portion of the discharge from 45 said stage into a second stage of lower pressure.
7. An elastic fluid turbine having a stage of high pressure, means for admitting fluid of high pressure to such stage, a stage of lower pressure receiving the fluid discharged from such high pressure stage, and a fluid compressing device coördinated with the stage of lower pressure in such a manner that fluid of low pressure and large volume will flow in circuit through the two, 50 means for operatively connecting fluid of high pressure and small volume with said device, whereby said device will be operated by the expansion of the high pressure fluid, and means for exhausting a portion of the discharge from 55 said stage into a second stage of lower pressure.

This specification signed and witnessed 75
this 12th day of December, 1911.
